ATTORNEY

UNITED STATES PATENT OFFICE.

OLOF BERNHARD DAHLQVIST, OF HUDIKSVALL, SWEDEN, ASSIGNOR OF ONE-HALF TO
PER ERIK WIKLANDER, OF HUDIKSVALL, SWEDEN.

REMOVABLE INNERSOLE FOR BOOTS OR SHOES.

Application filed March 13, 1925, Serial No. 15,216, and in Sweden May 9, 1922.

The present invention refers to an inner-
sole for insertion into boots or shoes, this
innersole being composed of three superim-
posed layers of materials, the uppermost,
5 level layer being provided with compara-
tively small holes, distributed over the whole
surface and the bottom layer being compact
or solid. The characteristics of this inven-
tion consist in the intermediate layer also
10 being level and provided with larger holes,
located about coaxially below the holes in
the top layer, their boundary walls with the
lowermost layer as a bottom forming cells
distributed over the entire sole, these cells
15 being closed with the exception of the small
holes in the top layer. By this means the
advantage is gained that these cells form an
air receptacle or air space into which the
transpiration from the foot is drawn
20 through the smaller vents in the top layer.
The air receptacles created by this means
are not interconnected. The bottom layer,
which is not provided with any holes, in-
sulates the foot from cold and damp in the
25 sole of the boot or shoe.

On the accompanying drawing is shown
only by way of an example an innersole for
boots or shoes constructed according to the
present invention, in Fig. 1 in vertical lon-
30 gitudinal section, in Fig. 2 seen from the
top and in Fig. 3 seen from below. Fig.
4 shows a detail of a fastener.

The innersole shown is composed of a
level, upper layer 1 which over its entire
35 surface is provided with small perforations
2, which are placed close to each other and
may be round, oval or of any other shape,
a level intermediate layer 3, provided with
larger perforations 5, coaxially located be-
40 low the holes 2, and which may be round,
oval or of any other shape, as well as a
level, compact or dense bottom layer 6 with-
out any holes. The three layers 1, 3 and
6 are similar in outline.

45 All parts are made of waterproof mate-
rial, e. g. of fibres treated with some cellu-
loid solutions such as dermatoid, pegamoid,
granitol etc. or some other suitable material.
Each one of the layers 1 and 6 may consist
50 of two layers secured together by means
of waterproof cement or glue, while the
layer 3 may consist of three layers secured

together in the same manner for obtaining
sufficient and necessary space in the per-
forations 5 forming the receptacles. All 55
the layers 1, 3 and 6 may also be of single
material of various thicknesses in the said
order.

In the example shown the top, interme-
diate and bottom layers are held together 60
by means of fasteners 7 placed in such spots
where there is no pressure from the foot.
These fasteners 7 are preferably made of
some material which is not affected by the
transpiration of the foot, cold or damp. 65
The fasteners may be easily detachable for
hygienic treatment of the innersoles and
for renewing the parts in the event of wear.
The perforations for the fasteners are pref-
erably provided with a special lining. The 70
fasteners may also be attached over the
edges of the innersoles in order to enable
them to be more easily taken apart. The
innersole may also be held together in some
other way than by fasteners and the 75
parts may in certain cases be left unse-
cured to each other. The edges of the holes
and the treads, as well as the edges of the
innersole may be reinforced by impregnat-
ing or painting them with a celluloid solu- 80
tion, e. g. by immersing the parts of the
innersole in the celluloid solution. The lay-
ers 1, 3 and 6 may be used separately if
desired.

I claim:—

A removable innersole for boots, comprising
85 three flat layers of compact material
disposed in superposed relation, said layers
being adapted to be separated one from the
other, the bottom layer being solid, the top
layer provided with comparatively small
90 perforations forming vents distributed over
the entire layer, and the intermediate layer
provided with larger perforations disposed
below the perforations in the top layer and
95 coaxial therewith, the boundary walls of
said larger perforations forming with the
bottom layer a series of cells distributed
over the entire composite sole, said cells be-
ing closed with exception of the small vents 100
in the top layer.

In testimony whereof I have signed my
name to this specification.

OLOF BERNHARD DAHLQVIST.
